DEVICE FOR CONFERENCE CALLS IN SUBSCRIBERS' DEVICES FOR LOUD AND FAINTLY AUDIBLE TRAFFIC

Otto Tschumi, Soleure, Switzerland, assignor to Autophon Aktiengesellschaft, Soleure, Switzerland, a joint-stock company of Switzerland

Application May 12, 1944, Serial No. 535,298
In Switzerland December 10, 1942

2 Claims. (Cl. 179—18)

1

This invention relates to devices for conference calls in subscribers' devices for loud and faintly audible signals.

If one of several subscribers should have the possibility of calling together any number of other subscribers for a loud or faintly audible telephonic conference, a considerable number of additional switch devices was hitherto necessary.

The device according to the invention allows switch devices already existing in the installation to be used in such a way that the above-mentioned connections become possible, thus allowing conference calls to be carried out economically.

The device according to the invention is characterised in that the means, serving in normal communication from subscriber to subscriber for changing-over loud to faintly audible signals, are used for switching-in the microphone of a subscriber wishing to speak at the conference.

The accompanying drawing illustrates, by way of example, one embodiment of the invention.

Figure 1 shows the diagram of a subscriber's device, and

Fig. 2 illustrates in a diagrammatic way that part of the main station which is necessary for the comprehension of the invention.

The electro-acoustic transformer EW shown in Fig. 1, according to the manner in which it is connected to the amplifier V, works as a loud-speaker or as a microphone. It is connected with the terminals a, b over the repeater Ue, the middle of the repeater-winding on the side of the line being in electric connection with the terminal a over the receiver T and the switch TK₁, so that by this current path one coil-half is bridged-over. The middle of an impedance coil Dr placed between the terminals a and b is connected with a rectifier arrangement over the contacts ES and e₂ which, in their turn, are bridged-over by the condenser CI. The rectifier arrangement is earthed over the impulse contact i of the calling dial NS and comprises an element (relay E) independent of the kind and direction of current and elements (relay U, optical signal SZ and resistance W₃) dependent on the kind and direction of current. Relay U can be disconnected from the rectifier arrangement by the switch TK₂ and the resistance W₃ by the switch TK₃. In Fig. 2 Tr means a transmission transformer. The middle of the winding of the transformer lying on the side of the main station can be connected alternately to a negative direct current potential or an alternating current source over the contacts k₁ and n₁. The transmission conductors

lead to the branch exchange final selector. Line n goes to the multiple contacts z₁ and z₂ which, as the multiple contact z₃, are controlled by the relay Z inserted into the n-line of the c-core. Relay Z is, similar to relay T_s, connected to a negative direct current potential, and its circuit is closed when it is connected by the branch exchange final selector LW_c to the positive side of a battery over relay K, relay P and the contact p.

Figure 3 shows the delay action relay N connected in series with the contact k₂.

If the subscriber of the subscriber's device illustrated in Fig. 1 wishes to call together a conference he establishes a connection with the terminals a, b of the transmission transformer Tr in Fig. 2 by dialling the dial NS. The final selector LW with its arms LW_a—c is now adjusted corresponding to the selecting impulses, for instance, adjusted on the line n. Thereby the above-mentioned circuit is closed for the relay Z, which results in the fact that by the multiple contacts z₁—z₃, the subscribers desired are selected and switched-in. Thereby, also the relays T₁ and T_s of the subscribers in question are operated so that they are locked against any further call.

Owing to the fact that the relay Z is of smaller resistance than relay T_s, into the place of which it steps owing to the selected number of impulses, relay K comes into action and by the contact k₁ causes, that in place of the normal voltage a short alternating voltage is given upon the subscribers' devices. The other contact k₂ of the relay K operates the delay action relay N effecting the disconnection of the alternating current source and the substitution of the latter by a negative direct current potential, so that only during the short period within which the attraction of the relay N is delayed with regard to relay K owing to the condenser connected in parallel, the subscribers' devices are supplied with alternating current.

This short alternating current impulse reaches over condenser CI the relay E of the rectifier arrangement which results in a connecting-in of the amplifier by the switches e₁ and e₂ and in the opening of a direct current path over the rectifier arrangement. Thereby, relay U is operated and all the stations in question are changed over to hearing condition.

If one of the subscribers called for the conference wishes to change over from hearing to speaking, he takes off the receiver T, thereby operating the switches TK₁—z₃. The relay U is disconnected from the circuit by switch TK₂, and the switches u₁ and u₂ change over the electro-

acoustic transformer EW to speaking conditions. TK₁ connects the receiver to the line, so that the speaking person can examine whether another person enters into conversation in his place. After having spoken the subscriber in question replaces the receiver T, switch TK₁ is opened, while switch TK₂ again connects in the relay into the direct current circuit, whereby EW is again changed over to speaking conditions.

As may be seen from the above, all the subscribers participating in the conference can by individual means establish conditions allowing them to speak. This coordination of the stations is only interrupted by the fact that the station having called together the conference has the additional possibility of establishing the speaking conditions by operating the calling dial NS.

Should some of the subscribers not desire to hear the conference through the loud-speaker, but only faintly audible, they may constantly hold the receiver to the ear, while the transformer EW remains continuously disconnected from the line by keeping open the contact AS.

These means, allowing any of the conference participants to insert himself as a speaker into the conversation, serve in normal traffic the purpose of changing-over a loud conversation into a faintly audible one and vice-versa in that, by removing the receiver, EW is changed-over to speaking conditions and receiver T connected to the line.

In this way, it is possible to combine both operations with the aid of the same switch devices which, besides a simple connection, results in smaller costs.

What I claim is:

1. In a telephone system for loud and faintly

audible communication, subscribers stations each including an electro-acoustic transformer serving as both a microphone and a loud-speaker, a line circuit, connections between said circuit and said electro-acoustic transformer, circuit control means operable to change said connections to render the electro-acoustic transformer operative as either a microphone or loud-speaker, means responsive to an incoming signal to operate the circuit control means and render the electro-acoustic transformer operative as a loud-speaker, a normally inoperative receiver for producing faintly audible signals, and switch means for operably connecting said receiver in said circuit and simultaneously rendering said signal responsive means inoperative whereupon said electro-acoustic transformer is rendered operative as a microphone by said circuit control means.

2. A telephone system as claimed in claim 1 wherein each subscribers station is provided with a calling dial for selecting other of said stations to be called.

OTTO TSCHUMI.
